FEEDING DEVICES FOR RECORD CARD MACHINES

Michael Maul, Schwabach, near Nurnberg, Germany

Application July 19, 1954, Serial No. 444,279

14 Claims. (Cl. 270—58)

In record card machines, such as in punched card controlled machines, feeding devices are provided by means of which the cards are fed along their card feeding path from a magazine to a receiving pocket. On their way from the magazine to the receiving pocket the cards are fed past analyzing devices, which analyze the controlling index marks of the cards (for instance holes), and which control accumulators or printing mechanisms according to the result of the analysis. The analysis may, however, also be effected merely for the purpose of comparing the perforations of different cards, or a punching means may be arranged in the card feeding path, subsequently providing the controlling cards with a perforation.

Now, it occurs in such machines that cards are mechanically advanced from two different magazines, said cards either having to be deposited in two separate receiving pockets or having to be interpolated according to certain points of view and in accordance with the result of the comparing analysis, and which then have to be deposited into a single common pocket, designated as the interpolating pocket. Such a machine is for instance known as a card interpolator.

If in machines of the indicated type the immediate comparison of the cards is effected during their movement past a row of analyzers, for instance past a row of analyzing brushes, this conditions the cards of the two stacks to be fed to their analyzing brushes in the same relative position so that always the same hole positions of the cards of the two kinds may be compared by the analyzing brushes simultaneously with each other. In this arrangement, the cards of the two stacks must run past the analyzing brushes with the upper card edge ahead. Now, if for instance the cards have to be fed to a common interpolating pocket in which they shall be deposited in corresponding positions, it is necessary that the two magazines be arranged on the same side (either left or right hand side) of the interpolating pocket. This results in a very unfavorable constructive solution for the feeding device of the cards and the associated analyzing devices, since both must be arranged above each other and since the lower feeding path together with its associated analyzing means is not easily accessible.

These disadvantages are avoided by the device according to the invention. The invention provides in the card feeding path a card turning device adapted to turn the cards in the card feeding plane through any desired angle. Thereby it becomes possible, for instance in machines serving for interpolating tasks, to arrange each of the two magazines on any of the two sides of the interpolating pocket and still to comply with the just mentioned condition of the simultaneous analysis of corresponding hole positions of the cards advancing from the two magazines but nevertheless to deposit all cards in the interpolating pocket in the same relative position. If turning of the cards in the card plane is effected through 180° as is the case in a preferred embodiment, the magazines may be provided on both sides of the interpolating pocket in such way that all the card pockets as well as their feeding devices are arranged in a straight line which results in a very pleasant appearance of the machine.

When applying the invention the cards may be deposited in the two magazines in such manner that the upper card edge advances in the feeding direction, so that always

2

identical hole positions of the cards of the two groups of cards may be analyzed by the analyzing means. However, as soon as comparison has been effected, the one card arrives under the card turner which will turn the same in the card plane through the desired angle without reversing it, and which will then again transfer the card to the feeding device, the latter feeding the card to the receiving pocket. After this turning movement, the card will be in the receiving pocket in the same position as the cards arriving from the other magazine so that, for instance, the usually cut off corners of all cards are in alignment.

The invention, however, does not only permit a constructively favorable arrangement of the supplying and analyzing means as well as an easy accessibility of the same but contrarily to the known devices it permits also to construct identical supplying devices for the two card stacks and the analyzing devices, thereby reducing the manufacturing costs of the machine. Finally it may be added that the magazines can be arranged by any desired angle with regard to the receiving pocket so that, for instance, the magazines and their feeding path may be arranged at a right angle with regard to the receiving pocket and notwithstanding the cards may be deposited in the same position relative to each other.

The inventive idea may be carried into practice in various ways. In an embodiment described hereafter, the card turning device consists of two pairs of feeding rollers rotating in opposite direction and being equally spaced from the feeding centre line, said rollers engaging the card as soon as the centre of the same arrives at the centre of the turning device. The rotating rollers are operatively so connected to the rollers which feed the card to the rotating rollers and remove it from the same, that the rotating rollers engage the card shortly before the supplying rollers are raised from the card and the removing rollers re-engage the card before it is released from the rotating rollers.

Further possible embodiments consist for instance in the arrangement of a gripper in the card feeding path in which the card is moved, said gripper imparting then to the card a rocking movement in the card plane and feeding the card to the removing rollers. For instance, turning disks which are pressed against each other as soon as the card is between them may be provided instead of the first mentioned rotating rollers or of the gripper, said disks imparting then to the card the rocking movement and afterwards supplying it again to the removing rollers.

If desired, also a deflector may be provided in the card feeding path ahead of the card turning device, said deflector deflecting the card from the card feeding path before it is supplied to the card turner and feeding it to a special receiving pocket. By means of this device the card may be selectively deposited into a special receiving pocket without receiving a turn, or be turned and then fed into the interpolating pocket.

The inventive device is particularly advantageous where cards are fed in opposite directions from two different magazines and where cards are to be deposited in a common pocket in the same relative position. The application of the invention is, however, not restricted to such machines. The invention may rather be applied wherever it is necessary for any reasons to deposit the cards in a position other than the one they had when being removed from the magazine.

In the accompanying drawings some embodiments of the invention for a card turn of 180° are illustrated, which, however, are chiefly restricted to the design of the card turning device proper. The particular type of machine in which the device is applied is not referred to in detail. The reason is that on the one hand such machines are known and on the other hand the invention

may be applied in the most different embodiments of the indicated machines.

Fig. 1 shows diagrammatically a machine in which cards are removed from the various magazines, said cards may then be deposited either commonly in an interpolating pocket or also separately.

Fig. 2 shows diagrammatically the position of the cards supplied to the interpolating pocket from opposite sides as well as the arrangement of the card turner.

Fig. 3 shows in plan the card turner which is arranged in the card path.

Fig. 4 shows the rear wall of the card turner with the drive of the latter.

Fig. 5 shows the front side of the card turner with the receiving pocket and the interpolating pocket.

Fig. 6 shows a side view from which particularly may be seen the arrangement of the turning rollers.

Fig. 7 shows in a perspective illustration an embodiment with a card turner provided as gripper.

Fig. 8 shows in a perspective illustration a further embodiment in which the card turner consists of two rotating disks.

It has been assumed that the machine, diagrammatically shown in Fig. 1, is a card interpolator in which the cards from the magazine 10 shall be interpolated between the cards from the magazine 11. The cards from the two magazines are fed in a known manner by feeding means past analyzing brushes and are compared with each other. The comparison is herein of no importance. The deposition of associated cards is effected in the interpolating pocket 12.

The diagram of the supply of the cards may be seen from Fig. 2. The cards advancing from the magazine 11 run ahead with the upper edge of the card and are deposited in the same position in the interpolating pocket 12 which is only diagrammatically indicated in Fig. 2, so that, accordingly, their cut off corners point down to the left. The cards from the magazine 10, however, must now also be fed ahead with the cut off corners so that the analyzing brushes may always analyze the same hole positions of the cards advancing from the two magazines. But if it would now be attempted to interpolate in the illustrated embodiment the cards advancing from the 10-pocket without application of the card turner, the cards in the interpolating pocket would not lie above each other in the same position: For the cut off corners of the cards advancing from the magazine 11 lie in the left lower corner of the interpolating pocket 12 (Fig. 2) while the cut off corner of the cards advancing from the magazine 10 would lie in the right upper corner of the interpolating pocket 12. The proper position of the cards relative to each other is, however, obtained by the card turner according to the invention. The latter is provided behind the analyzing devices in the card feeding path of the cards advancing from the magazine 10 and turns the card in the feeding path for 180° before the latter is supplied to the interpolating pocket 12. In the latter the cards arriving from the magazine 10 will, therefore, have the same position as the cards arriving from the magazine 11, as may also be seen from Fig. 2.

The preferred embodiment, illustrated in Figs. 3 to 6, uses two pairs of rollers arranged symmetrically to the centre line of the card feeding path. As soon as the card is engaged by said two pairs of rollers, they impart to the card a turning or rocking movement through 180° since the pairs of rollers rotate in opposite directions relatively to each other. The card is fed to the removing rollers after the 180° rotation. The card turning device, according to Figs. 3 to 6, is constructed in detail as follows and operates as will now be described:

After the analysis the card is supplied by means of the feed rollers provided upon the shaft 14 (Fig. 3) to the turning device and is fed so far until the front edge of the card has passed between the faster running rollers 16.

75

The latter engage the card and feed the same under the pairs of turning rollers 17 and 18. The higher speed of the rollers 16 with regard to the feed rollers 15 has been provided in order to obtain a sufficiently large distance from the following card and in order to prevent a relative disturbing of the cards during the turning movement. Accordingly, the rollers 16 feed the card between the pairs of turning rollers 17 and 18, and in such way that the centre of the card is under the rollers, as may be seen from Fig. 3.

The turning device is driven through the belt disk 19 which is rigidly connected to the toothed sectors 21 and 22 (Figs. 4 and 6) and mounted together with the same upon the stud 30. The toothed sector 21 drives by means of the toothed wheels 23 and 26 the rollers 16 upon the shafts 24. The drive of the two turning rollers 17 is effected by the toothed sector 22 which drives the toothed wheel 27, rigidly provided upon the shaft 25. The toothed wheel 28, also fast upon the shaft 25, is engaging the toothed wheel 29 upon the shaft 31. The two shafts 25 and 31 carry in addition the one pair of turning rollers 18. On the front side of the turning device there is provided an idle gear 33 mounted on an angle 32 (Figs. 5 and 6), said gear meshing with the gear 34 being fast upon the shaft 31 and transferring the movement of the latter to the gear 36. The latter is fast on the sleeve 35. The gear 37, also fast on the sleeve 35, will then drive the gear 39 connected to the sleeve 38. By the insertion of an idle gear 33 it will be obtained that the sleeve 38 rotates contrarily to the shaft 31, and the sleeve 35 contrarily to the shaft 25, so that the card is turned as is indicated by the arrow in Fig. 3.

To avoid simultaneous engagement of the card by the feeding rollers 16 and the turning rollers 17 and 18, a lifting device is provided so that alternately the feeding rollers and then the turning rollers act on the card. The reverse control is effected by a slide 41 (Figs. 4 and 5) provided with inclined planes and adapted for reciprocating movement in the guiding pieces 42 and 43. A lever 45 which is fast upon the shaft 44 is controlled by a cam 46, said cam being connected to the belt disk 19, synchronously with the card feed.

At the front side of the turning device there is mounted on the shaft 44 a lever 47 which transfers the movement to the front slide 48 carrying a stud 49 slidably guided in an elongated hole 51 of the lever 47. Lever 45 has a corresponding stud, not shown, engaging a corresponding slot (not shown) in slide 41 so that slide 41 is moved by the lever 45. The two levers are drawn by the springs 52 to the right of Fig. 4 and to the left of Fig. 5, respectively, until the lever 45 engages the cam disk 46. The two slides are herein carried along in accordance with the cam position. By means of the slides 41 and 48 the shaft 31 is somewhat lifted in the position shown in Fig. 4 and therewith are also lifted the upper turning rollers 17 and 18. In this position the slide has no influence upon the two shafts 24 with the rollers 16 so that the rollers 16 are pressed against the card under spring action and then feed the card.

If the card center is exactly between the turning rollers 17 and 18, the cam 46 will move the lever 45 and the latter will move the slide 41 to the left (Fig. 4) while the lever 47 moves the slide 48 to the right (Fig. 5). The inclined guide faces of the two slides are arranged in such way that during movement to the left or to the right, respectively, first the turning rollers 17 and 18 will engage the card whereupon shafts 24, and therewith the rollers 16 are raised. Now, the turning rollers will act upon the card while the rollers 16 are raised. This position is shown in Figs. 5 and 6.

After completion of the turn (the sector 21 and the rotating rollers 17, 18 are dimensioned in such way that the card rotates exactly for 180°) the cam 46 permits the lever 45 to rock to the right (Fig. 4) under the in-

fluence of spring 52. The lever 47 (Fig. 5) rocks correspondingly to the left. Herein, the two levers carry along with them their slides 41 or 48, respectively, so that the rollers 16 lower upon the card. Shortly thereafter, the turning rollers are lifted. The upper shafts 24 as well as shaft 31 and sleeve 38 are mounted in elongated holes of the side walls and are pressed downwardly by springs which are not illustrated herein.

If it is not intended to interpolate the cards but to deposit them separately a deflector 53 (Fig. 5) is rocked in clockwise direction about the shaft 54 so that the cards are not supplied to the rollers 16 but to the receiving pocket 13. This deflector may of course be put in a known manner under the control of the comparing device so that depending on the comparison the cards may be deposited selectively into any one of the two depositing pockets.

A further embodiment is shown in Fig. 7. The card is supplied to the rollers 61, as it is indicated by the arrow. As in the above described embodiment these rollers run faster than the regular feed rollers, in order to obtain the lead necessary for the turning movement. The lower rollers 61 are seated upon a shaft mounted in the side-walls while the upper rollers 61 are seated in a shaft mounted in the two levers 62. The levers 62 are mounted upon the shaft 63. The card is moved upon the base plate 64 of a gripper by means of the rollers 61.

Shortly before the leading edge of the card engages the metal sheet 65, being slightly resilient and seated on the base plate, the upper rollers 61 are lifted by means of the cams 66 and the levers 62. The cams rotate synchronously with the card movement. The crank 67 rotates also synchronously with the card movement and imparts to the arm 68 upon the shaft 71 a rocking movement through the link 69. On the shaft 71 is further provided an arm 72 upon which is mounted the sleeve 73. The latter carries on its upper end the gripper 64. On the lower end of the sleeve there is fastened a toothed wheel 74 cooperating with a toothed segment 76 which is arranged on a stationary plate 75. Now, if the arm 72 turns in counter-clockwise direction, the toothed wheel 74 will turn in clockwise direction so that through sleeve 73 also the gripper is turned, and it will be seen that the extension of the rocking movement is such, that the toothed wheel 74 and the gripper perform exactly half a revolution.

Just at the beginning of the rocking movement of the arm 72, the slightly resilient metal sheet 65 slides off the stop bar 77 and presses the card against the plate 64 of the gripper. Accordingly, the card is taken along and is thereby simultaneously turned through 180°. At the end of the rocking movement the gripper moves the card between the rollers 78 and rollers 79 which are disengaged at this moment. The shaft 81 with the rollers 78 is mounted in the two levers 62. When the turning movement is finished and if the card is between the rollers 78 and 79, the levers 62 slide off the cams 66 and are drawn downwardly by the springs 82 whereupon the rollers 78 press on the card. The latter is engaged by the rollers 78 and 79 and is fed to the interpolating pocket. Simultaneously therewith, the arm 72 returns again to its initial position and the gripper turns in counter-clockwise direction. Shortly before the end of the rocking movement the metal sheet 65 engages the stop 77 and is somewhat lifted from the base plate 64 so that another card can be received.

For reasons of clarity the drive of the rollers 61, 78 and 79 as well as that of the cam disks 66 has not been illustrated.

Fig. 8 shows a third embodiment. The card is moved between the rollers 86 and 87 in the direction of the arrow and is engaged by the same and fed between the two rotating disks 88 and 89. Shaft 92 is movable with levers 91, and the shaft which carries rollers 87 is mounted on a stationary support. Levers 91 are pivotally

mounted in the machine frame by pins 98. When the center of the card is exactly between the rotating disks 88, 89, the cam disks 95 permit the stirrup 97 to move the levers 91 upwardly under the action of springs 96. 5 Shaft 92 with the rollers 86, and a shaft 93 with the rollers 94 are mounted on levers 91, and stop 99 prevents further advancing of the card.

Upon its lifting movement the stirrup 97 raises the axially movable rotary disk 89 through shaft 101 so that 10 the card is held between the two rotating disks 88 and 89. The lower rotating disk is rotatably mounted upon shaft 101. As soon as the card is only held by the rotating disks, the toothed section 102 which reciprocates once per card cycle will engage the toothed wheel 103 15 whose radius is chosen in such way that the toothed wheel 103 performs during one full reciprocation of the toothed sector 102 half a revolution in counter-clockwise direction and then half a revolution in clockwise direction. The shaft of gears 103, 104 is turnably mounted on the 20 machine frame. This movement is transferred through a pair of bevel gears 104, 105 to the upper rotating disk 88. The rotating disks turn in the feeding path and turn the card 180° in clockwise direction. Thereby the card is moved between the rollers 94 and 106. Rollers 94 25 are raised at this time. Rollers 106 are turnable with a shaft which is mounted in a stationary supporting part of the machine. When the card is between the rollers 94 and 106 the cam disks 95 effect downward movement of shaft 93 with the rollers 94 by means of levers 91, 30 whereupon the card is gripped by the rollers 94 and rollers 106, and since at the same moment the card is released by the rotating disks it is fed by the rollers 94 and 106 to the receiving pocket. The upper rotating disk 88 returns again to its normal position and the cycle 35 may begin anew.

It may be seen that the inventive idea can be carried into practice in various manners. It can also be readily realized that the invention may be adapted to any desired turning angle since for this purpose it is only necessary to provide the ratio between the card turner and its drive accordingly, and to position the axes of the removing rollers in such way that they are in parallel with the leading card edge after the turn of the card.

I claim:

1. Feeding and positioning apparatus for cards provided with controlling marks and having top and bottom faces, the apparatus comprising, in combination, a card receiving member; first feeding means for feeding a first group of said cards along a first feeding path in a first feeding direction toward said receiving member; second feeding means for feeding a second group of said cards in a second feeding direction along a second feeding path toward said receiving member, said second feeding means including feeding elements defining a portion of said second feeding path, said feeding elements being movable between an inoperative position and an operative position for feeding cards fed to said portion further along said second feeding path; card turning means located in said portion of said second feeding path and being movable between an inoperative position and an operative position, said card turning means being adapted to engage in said operative position cards fed to said portion of said second feeding path for turning the cards through a selected angle about an axis transverse to said top and bottom faces, said selected angle corresponding to the angle between said first and second directions; and means for simultaneously moving said feeding elements to said inoperative position and said card turning means to said operative position and for simultaneously moving said feeding elements to said operative position and said card turning means to said inoperative position.

2. Feeding and positioning apparatus for cards provided with controlling marks and having top and bottom faces, the apparatus comprising, in combination, a card receiving member; first feeding means for feeding a first

group of said cards along a first feeding path in a first feeding direction toward said receiving member; second feeding means for feeding a second group of said cards in a second feeding direction along a second feeding path toward said receiving member, said second feeding means including feeding elements defining a portion of said second feeding path located in a plane, said feeding elements being movable between an inoperative position and an operative position located in the plane for feeding cards fed to said portion further along said second feeding path with said top faces on top and located substantially in said plane; card turning means located in said portion of said second feeding path and being movable between an inoperative position and an operative position located in said plane, said card turning means being adapted to engage in said operative position cards fed to said portion of said second feeding path for turning the cards in said plane through a selected angle about an axis transverse to said top and bottom faces and to said plane, said selected angle corresponding to the angle between said first and second directions; and means for simultaneously moving said feeding elements to said inoperative position and said card turning means to said operative position and for simultaneously moving said feeding elements to said operative position and card turning means to said inoperative position.

3. Feeding and positioning apparatus for cards provided with controlling marks and having top and bottom faces, the apparatus comprising, in combination, a card receiving member; first feeding means for feeding a first group of said cards along a first feeding path in a first feeding direction toward said receiving member; second feeding means for feeding a second group of said cards in a second feeding direction along a second feeding path toward said receiving member, said second feeding means including feeding roller elements defining a portion of said second feeding path, said feeding roller elements being movable between an inoperative position and an operative position for feeding cards fed to said portion further along said second feeding path, said feeding roller elements rotating at a greater peripheral speed than the part of the second feeding means located outside of said portion of said second feeding path; card turning means located in said portion of said second feeding path and being movable between an inoperative position and an operative position, said card turning means being adapted to engage in said operative position cards fed to said portion of said second feeding path for turning the cards through a selected angle about an axis transverse to said top and bottom faces, said selected angle corresponding to the angle between said first and second directions; and means for simultaneously moving said feeding roller elements to said inoperative position and said card turning means to said operative position and for simultaneously moving said feeding roller elements to said operative position and said card turning means to said inoperative position.

4. In a machine controlled by cards provided with controlling marks and having top and bottom faces and a position determining edge, in combination, a card receiving pocket; first feeding means for feeding a first group of the cards in a feeding plane along a first feeding path in a first feeding direction towards and into said receiving pocket with said edge of each card leading in feeding direction so that said cards are deposited in said receiving pocket with said edges superimposed and said top faces on top; second feeding means for feeding a second group of cards in a feeding plane in a second feeding direction along a second feeding path with said edges of said cards of said second group of cards leading in said second feeding direction, said first and second feeding directions defining a predetermined angle with each other; turning means at the end of said second feeding path for turning the cards of said second group about an axis transverse to said top and bottom faces and

through an angle corresponding to said predetermined angle; and third feeding means for feeding the thus turned cards of said second group from said turning means into said receiving pocket so that said cards of said second group of cards are deposited in said receiving pocket with said edges of the same superimposed on each other and on said edges of said first group of cards and with said top faces on top.

5. In a machine controlled by cards provided with controlling marks and having top and bottom faces and a position determining edge, in combination, a card receiving pocket; first feeding means for feeding a first group of the cards in a feeding plane along a first feeding path in a first feeding direction towards and into said receiving pocket with said edge of each card leading in feeding direction so that said cards are deposited in said receiving pocket with said edges superimposed and said top faces on top; second feeding means for feeding a second group of cards in a feeding plane in a second opposite feeding direction along a second feeding path with said edges of said cards of said second group of cards leading in said second opposite feeding direction; turning means at the end of said second feeding path for turning the cards of said second group about an axis transverse to said top and bottom faces and through an angle of 180°; and third feeding means for feeding the thus turned cards of said second group from said turning means into said receiving pocket so that said cards of said second group of cards are deposited in said receiving pocket with said edges of the same superimposed on each other and on said edges of said first group of cards and with said top faces on top.

6. In a machine controlled by cards provided with controlling marks and having top and bottom faces, in combination, a card receiving pocket; first and second feeding means for feeding cards with said top faces on top in opposite feeding directions along first and second aligned feeding paths toward and into said receiving pocket; and card turning means located in said first feeding path for turning fed cards through an angle of 180° about an axis transverse to said top and bottom faces so that said cards are deposited in said receiving pocket in corresponding positions with said top faces on top.

7. Feeding and positioning apparatus for cards provided with controlling marks and having top and bottom faces, the apparatus comprising, in combination, feeding means for feeding the cards along a feeding path and including feeding elements defining a portion of said feeding path located in a plane, said feeding elements being movable between an inoperative position and an operative position located in said plane for engaging and feeding cards fed to said portion further along said feeding path with said top faces on top and located substantially in said plane; card turning means including a pair of rollers rotating in opposite directions about an axis transverse to said feeding path and being equally spaced from the longitudinal line of symmetry of said feeding path, and another pair of rollers cooperating with said first-mentioned pair of rollers and rotating in opposite directions, at least one of said pairs of rollers being movable between an inoperative position spaced from the other pair of rollers and an operative position located in said plane, said pairs of rollers being adapted to engage in said operative position the top and bottom faces of cards fed to said portion of said feeding path for turning the cards through a selected angle about an axis transverse to said top and bottom faces and to said plane; and means for simultaneously moving said feeding elements to said inoperative position and said one pair of rollers to said operative position and for simultaneously moving said feeding elements to said operative position and said one pair of rollers in said inoperative position.

8. Feeding and positioning apparatus for cards provided with controlling marks and having top and bottom faces, apparatus comprising in combination, feeding

means for feeding the cards along a feeding path and including feeding elements defining a portion of said feeding path located in a plane, said feeding elements including two pairs of top feeding rollers, two shafts respectively connecting said pairs of top feeding rollers and two pairs of cooperating bottom feeding rollers; support means supporting said shafts and said top feeding rollers for movement between an inoperative position spaced from said bottom feeding rollers and an operative position located in said plane for engaging and feeding cards fed to said portion further along said feeding path with said top faces on top and located substantially in said plane; card turning means located in said portion of said feeding path and including a pair of top turning rollers rotating in opposite directions about an axis transverse to said feeding path and being equally spaced from the longitudinal line of symmetry of said feeding path, and a pair of bottom turning rollers cooperating with said pair of top rollers and rotating in opposite directions, two shaft means respectively connecting said top turning rollers and said bottom turning rollers, each shaft means including a sleeve and a shaft turnable in said sleeve, said support means supporting the shaft means associated with said top turning rollers for movement between an inoperative position in which said top turning rollers are spaced from said bottom turning rollers and an operative position located in said plane, said pairs of top and bottom turning rollers being adapted to engage in said operative position the top and bottom faces of cards fed to said portion of said feeding path for turning the cards through a selected angle about an axis transverse to said top and bottom faces and to said plane; cam slide means mounted on said support and engaging said shaft means associated with said top turning rollers and said shafts associated with said top feeding rollers, said cam slide means being movable between two positions for moving said top feeding rollers to said inoperative position and said top turning rollers to said operative position, and for moving said top feeding rollers to said operative position and said top turning rollers to said inoperative position; drive means for rotating said feeding rollers and said turning rollers; and transmission means connecting said drive means with said slide cam means for moving said slide cam means at selected time intervals between said positions of the same.

9. An apparatus as claimed in claim 8 wherein said transmission means include lever means connected to said cam slide means; turnable cam means engaging said lever means; and gear means connecting said drive means with said cam means.

10. An apparatus as claimed in claim 8 wherein said cam slide means have a cam track of such shape that said turning rollers are held in said operative position until a card engaged by the same is turned through 180°.

11. Feeding and positioning apparatus for cards provided with controlling marks and having top and bottom faces, apparatus comprising in combination, a card receiving member; first feeding means for feeding a first group of said cards along a first feeding path in a first feeding direction toward said receiving member; second feeding means for feeding a second group of said cards in a second feeding direction along a second feeding path toward said receiving member, said second feeding means including feeding elements defining a portion of said second feeding path located in a plane, said feeding elements including two pairs of top feeding rollers, two shafts respectively connecting said pairs of top feeding rollers and two pairs of cooperating bottom feeding rollers; support means supporting said shafts and said top feeding rollers for movement between an inoperative position spaced from said bottom feeding rollers and an operative position located in said plane for engaging and feeding cards fed to said portion further along said second feeding path with said top faces on top and located substantially in said

plane; card turning means located in said portion of said second feeding path between said two pairs of top feeding rollers and said two pairs of bottom feeding rollers and including a pair of coaxial discs having engaging faces parallel to said plane and being turnable through a selected angle about an axis transverse to said plane and to said top and bottom faces of said cards, said selected angle corresponding to the angle between said first and second directions, one of said discs being movable between an inoperative position spaced from the other disc and an operative position in which said faces are substantially located in said plane for engaging said top and bottom faces of the cards; means for turning said discs through said selected angle for turning said cards about an axis transverse to said top and bottom faces; and means connected to said shafts of said top feeding rollers and to said one disc for simultaneously moving said top feeding rollers to said inoperative position and said discs to said operative position, and for simultaneously moving said top feeding rollers to said operative position and said one disc to said inoperative position.

12. An apparatus as set forth in claim 11 wherein said shafts of said top feeding rollers are parallel and said selected angle is 180°.

13. Feeding and positioning apparatus for cards provided with controlling marks and having top and bottom faces, apparatus comprising in combination, a card receiving member; first feeding means for feeding a first group of said cards along a first feeding path in a first feeding direction toward said receiving member; second feeding means for feeding a second group of said cards in a second feeding direction along a second feeding path toward said receiving member, said second feeding means including feeding elements defining a portion of said second feeding path located in a plane, said feeding elements including two pairs of top feeding rollers, two shafts respectively connecting said pairs of top feeding rollers and two pairs of cooperating bottom feeding rollers; support means supporting said shafts and said top feeding rollers for movement between an inoperative position spaced from said bottom feeding rollers and an operative position located in said plane for engaging and feeding cards fed to said portion further along said second feeding path with said top faces on top and located substantially in said plane; card turning means located in said portion of said second feeding path between said two pairs of top feeding rollers and said two pairs of bottom feeding rollers and including a gripper means adapted to engage cards fed to said portion, said gripper means being turnable about an axis transverse to said plane and to said top and bottom faces of said cards; means for turning said gripper means through a selected angle in opposite directions for turning said cards about said selected angle and for transferring the cards from one group of cooperating pairs of top and bottom rollers to the other group of cooperating pairs of top and bottom rollers, said selected angle corresponding to the angle between said first and second directions; and means connected to said shafts of said top feeding rollers and to said gripper means for simultaneously turning said gripper means and for moving said top feeding rollers to said inoperative position.

14. An apparatus as set forth in claim 13 wherein said shafts connecting said top feeding rollers are parallel and said selected angle is 180°.
